GEORGE W. KNAPP, OF BALTIMORE, MARYLAND, ASSIGNOR TO NATIONAL ENAMELING AND STAMPING COMPANY, OF BALTIMORE, MARYLAND, A CORPORATION OF NEW JERSEY.

HANDLE-SOCKET FOR DIPPERS.

No. 914,352.

Specification of Letters Patent.

Patented March 2, 1909.

Application filed October 14, 1908. Serial No. 457,620.

To all whom it may concern:

Be it known that I, GEORGE W. KNAPP, a citizen of the United States, residing at Baltimore, in the State of Maryland, have invented certain new and useful Improvements in Handle-Sockets for Dippers, of which the following is a specification.

This invention relates to a sheet-metal handle-socket for dippers.

10 Sockets for the wood-handles attached to sheet-metal vessels have heretofore been made from a flat blank by bending the blank into a tubular form and uniting the edges by a longitudinal seam; sockets of this character have the merit of being produced cheaply. In sockets thus made the wood handle has been prevented from disengagement by one or more pins or screws through the wall of the socket, but this is an unsatisfactory means for confining the handle because when the end of the wood handle that is within the socket shrinks, the handle at once becomes loose and shaggy. It is also well-known that seamless sheet-metal sockets have been made and that screw-threads have been formed in such sockets to confine the wood handle. While the handle may be kept tight in this kind of a socket, the socket itself is too expensive to manufacture for 30 low-priced goods.

One object therefore of the present invention is to produce a cheap metal socket in which a wood handle may be confined and always kept tight.

35 Another object is to provide an improved construction of handle-socket made from a flat sheet-metal blank that is coiled—the coil being united by a longitudinal lock-seam, and having in that side only of the socket 40 which is diametrically opposite the lock-seam a short diagonal indentation.

The invention is illustrated in the accompanying drawing wherein—

Figure 1 is a perspective view of a dipper 45 having the improved socket. Fig. 2 shows the socket in section and the end of the wood-handle in the socket. Fig. 3 shows a broken portion of the dipper bowl and the socket attached.

50 The bowl, 1, may be of any shape and made in any manner; the handle, 2, is designed to be made of wood and the end of the handle adjacent the bowl is slightly tapered and has a screw-thread, 3, that may 55 be formed by any means.

The improved socket, 4, which is the subject of the present invention is made from a sheet-metal blank (not shown). The socket slightly tapers and is coiled around and the coil is united by a longitudinal lock-seam, 5. 60 The smaller end of the socket has two ears, 6, bent laterally and adapted to fit against the outside of the bowl, 1, to which they are attached by rivets; these secure the socket firmly to the bowl. 65

One end of the wood handle fits snugly in the tapered socket, and it is desirable to avoid the use of pins or screws through the wall of the socket to prevent the handle disengaging because wood handles fastened by pins soon become loose. At that side of the socket which is diametrically opposite the lock-seam, 5, is an indented portion, 7, of a screw-thread; this indentation extends diagonal with respect to the axis of the 70 socket and for a distance of only about one fourth of the circumference. It will be seen that it is not practical to form a screw-thread all around the wall of the socket on account of the longitudinal seam. 75

The indentation, 7, forms an inward projection at the interior of the socket, and this inward projection presses into the wood at the screw-thread part, 3, when the handle is turned. The taper of the end of the wood- 80 handle, and the short diagonal indentation, 7, in the socket, will enable the handle to be kept tight even when the wood shrinks. 85

Having thus described my invention what I claim and desire to secure by Letters Patent is,—

1. A dipper socket consisting of sheet-metal coiled and having a longitudinal seam and provided at the side opposite the seam with a short diagonal indentation. 90

2. A dipper bowl having a metal socket provided with a longitudinal lock-seam, and having at that side only which is diametrically opposite the said seam an indentation, 7, and a wood handle having its end tapered and screw-threaded and attached to said socket. 100

In testimony whereof I affix my signature in presence of two witnesses.

GEORGE W. KNAPP.
